HYDRAULIC TIE PULLER

Harry B. Hughes, Bandon, Oreg.

Application January 17, 1940, Serial No. 314,350

7 Claims. (Cl. 104—9)

My invention relates to fluid operated tie pulling devices, and has reference particularly to a device that is adapted for being moved along a rail track and for being spotted upon the rails of the track and for imparting endwise movement of the ties disposed within the track to aid in their expeditious removal.

Heretofore, it has been the general custom in the replacing of railway ties to loosen the ballast disposed at either side of the tie and beneath the tie and to then remove the tie by hand. This is a laborious task, requiring great physical effort. In addition thereto, the disturbance of the ballast in the track at either side of the tie and beneath the tie results in an uneven track support in the density of the ballast material to thereby disturb the safety of the track; one that affects train operation thereover, and particularly passenger trains. This was not so important when passenger trains moved at nominal speeds, but in these times of high speed operation for trains, the maintaining of the track in precise alignment is of fundamental importance. Also in these times of economic stress in railroad operation and control, it is necessary to practice economies in all lines of railroad operation.

Through the use of my new and improved tie puller, the amount of physical effort required of the section crew is greatly reduced, and the maintaining of the rails of the track in precise alignment results.

Also through the use of my new and improved device, an old tie may be removed and a new tie be replaced in the track without unduly disturbing the ballast in the road bed. By the older methods of hand removal, because of the disturbance in the rail bed, it was not found expeditious to remove single ties even though they had disintegrated. Or, if a single tie were removed, many times adjacent ties were also removed in order to maintain a uniform density of ballast within the track.

Through the use of my new and improved device, it is now possible to remove single ties and to replace the same with a new tie with very little disturbance to the ballast being required.

Also through the use of my new and improved tie puller, it is now possible to remove the tie and to replace the same with a fraction of the time being required in the operation that was formerly required to thereby permit the complete removal of a tie and the replacement of the same with another tie between passage of

trains thereover. This also is important in the safety of passenger train operations at high speeds.

I am aware that heretofore mechanical track jacks have been used, and that some attempts have been made to provide tie pullers that are strictly mechanical in their operation, but I am not aware that hydraulic tie pullers have been made. In most of the tie pullers heretofore used, the tie puller was mounted upon but one of the rails of the track and where substantial pulling effort was imparted to the tie, the kinking of the rail or the spreading of the rail members many times resulted.

I have overcome this objection and this tendency in my new and improved device by imparting like strain to both of the rails simultaneously.

In order to lessen the physical strain upon the track crew, I have also provided a prime mover for performing the actual work in the tie removal. This is also a great aid to the track crew particularly in those sections of the country where high temperatures and great humidity are experienced in the summer, and where extremely low temperatures are experienced in the winter time.

Through the use of my new and improved device, single ties may be removed or a group of ties in the same location may be removed with equal facility and with a minimum of time being consumed.

Also, my device being portable, it may be used by several section crews throughout the season to thereby limit the number of tie pullers being required to be purchased by the railroads using the same.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. I is a side view of one of my new and improved devices of the hand operated type shown in position for the removal of a tie from placement.

Fig. II is a top plan view of the mechanism illustrated in Fig. I.

Fig. III is an end view of the power driven supported device shown in place for being rolled along the track for placement and illustrating

the same as being used in the forcing of an old tie from placement and the pulling of a new tie into its place and position.

Fig. IV is a plan view of the assembled device.

Fig. V is a sectional side view of the device illustrated in Fig. IV.

Fig. VI is a side view, partially in section, of the assembled device illustrating the same in place and in position for ejecting a tie from placement.

Fig. VII is a partial plan view of one of the ejector heads shown in placed position.

Fig. VIII is a sectional side view of the head illustrated in Fig. VII.

Like reference characters refer to like parts throughout the several views.

Heretofore in power devices for the removal of ties from placement in railway tracks, the ejector or shoe has been made to engage the top side of the tie, the engagement being made through the application of downward pressure upon the ejector head. This mode of procedure created added friction between the bottom of the tie and the ballast structure upon which the tie rested to thereby require greater and substantially more pressure being applied in the ejecting of the tie.

To overcome this objection I have provided the ejector head so as to engage the top side of the tie and the opposite vertical edges of the tie simultaneously to prevent undue downward pressure to be applied to the top of the tie. By engaging the side walls of the tie with the ejector head it permits the carrying of the tie in suspension during its ejection to thereby lessen the amount of ejection force required in the pushing of the tie from its bed and its placement within the track.

In devices for this purpose it is equally important to provide means through the application of which the new tie may be placed in position after the old tie has been removed. This I provide by having an applicator head that may be applied to the older tie between the rails and to the end of the tie disposed outside of the rail so that in the placing of the new tie in position in the final stages of the operation, the old tie may be finally pushed from placement as the new tie is finally placed in its ultimate and final position.

In Figs. I and II I have illustrated one of my new and improved tie ejectors that is manually powered, illustrating the same upon a railway track comprised of rails 1 and 2. The rails are spaced apart in the usual manner and are supported upon ties. I have here shown the device as being comprised of a head 3. The head 3 has a foot 4 disposed upon its bottom end to adapt the same for engaging one side of the ball of the rail 1. In order to prevent the kinking of the rail 1 I have found it desirable to provide a tensioning member 5 that is secured to the head 3 and outwardly extends therefrom to provide a boot 6 that also engages the ball of the rail 2. In order to compensate for different gages of the rails which are not always spaced apart in like amount, I place a turn buckle 7 within the tensioning member 5 which is comprised of two parts as illustrated at 5 and 5A to provide adjusting means between the boot 6 and the foot 4.

A hydraulic cylinder 8 is provided. The hydraulic cylinder 8 is hingedly supported to the head 3 by pintle shafts 9 that outwardly extend

from the opposite sides of cylinder 8. The cylinder 8 has a piston not here shown to which is secured the piston rod 10. The piston rod 10 is made of the ram type. The ejector head 11 is hingedly secured to the piston rod 10 by a wrist pin 12. The head 11 has a plurality of teeth 12A disposed upon its underside that are fashioned to engage the top of the tie. In order to provide a substantial support for the cylinder 8 I provide a supporting arm 13 that is secured to the head 3 and outwardly extends therefrom. A cushioning support as a coil spring 14 is disposed between the end of the arm 13 and the cylinder to thereby compensate for the position of the cylinder and to support the same in adjusted position and to permit the same being hingedly adjusted about the pintle shafts 9. A pumping cylinder 15 is mounted relative to the primary cylinder 8. The pumping cylinder 15 has a piston disposed therein. A piston rod 16 is secured to the piston and outwardly extends therefrom. A pump handle 17 is provided. The pump handle 17 is secured on its lower end to a link 18. The link 18 connects the lower end of the handle 17 to the outer end of the piston rod 16. The link 18 is in articulate relationship relative to the handle 17 and the piston rod 16. The handle is supported upon a pin 19. A sump 20 is made available for securing of fluid for operating the piston within the cylinder 8. A suitable piping 21 communicates the pump 15 with the sump 20. Piping 22 and 23 communicate the valve 24 with the respective ends of the cylinder 8. When the ejector head 11 is in contact with the tie 25 an up and down movement may be imparted to the cylinder 8, and to the ejector head 11 by the hand manipulation of the cylinder to thereby aid in the ejection of the tie 25 from placement and position.

In order to further stabilize the rails 1 and 2 a bridging board 26 is provided that is made to engage the ends of the ties 27 and 28 with a gap in the board 26 through which the tie 25 is pushed. The tie puller is placed adjacent to the tie 25 that is being pushed from placement. A hand lever 29 is provided for the manipulation of the valve 24 and to predetermine the direction of movement of the piston to be actuated when the operating fluid is pumped from the pump 15 into the cylinder 8.

In Figs. III to VI inclusive I have shown a wheel supported chassis 30. A shaft 31 passes through suitable journal bearings and suitable flanged wheels 32 are mounted upon the respective shafts 31, the shafts being two in number and the wheels being four in number for each tie puller. The top 33 and the downwardly extending head supports 34 and the chassis are supported upon pistons 35. The pistons 35 have a piston head covering 36. The pistons 35 operate within suitable cylinders 37 with each of the pistons having a piston rod 38 that operates as a guide within the journal blocks 39 through which the respective shafts 31 pass. A plurality of tie engaging heads, here shown as four in number, at 40, 41, 42, and 43 are mounted upon a ram shaft 44. The ram shaft 44 is also a piston rod with the piston rod running longitudinally through a cylinder 45. The cylinder 45 has heads disposed in its opposite ends with suitable packing clamps 46 and 47. A piston 48 is fixedly positioned upon the piston ram shaft 44 and is adapted for being reciprocated longitudinally of the cylinder 45. It is of importance in devices of this kind that the respective balls of the respec-

tive rails 49 and 50 be engaged when pressure is to be applied in the pulling or the pushing of the tie in placement to prevent the pushing of the respective rails from alignment and for preventing the disturbing of the track gage.

It is also of fundamental importance in the pushing of the old tie from placement or the pulling of the new tie into placement that a minimum of downward pressure be applied to the tie to create added frictional resistance between the bottom of the tie and the ballast in which the same has been or is to be imbedded by the forceable engaging of the respective heads 40 to 43 inclusive, with the top surface of the tie and with the opposite vertical edges of the tie. Then, by raising the chassis and the tie engaging heads by the admission of a fluid into the cylinder 37 and below the piston 35, the tie may be carried in suspension and with its top surface in contact and engagement with the underside of the base of the respective rails 49 and 50, to thereby prevent undue friction being developed between the underside of the tie and the ballast.

It is also important in order to conserve time and to prevent other ballast falling into the bed from which the old tie is to be removed. That is accomplished by the end abutment of the tie 51 that is being removed and the tie 52 that is to replace the tie 51, being made to engage each other as illustrated at 53 in Fig. V so that as the new tie is being drawn into place as the old tie is being removed that an uninterrupted tie be maintained, to thereby eliminate and prevent ballast entering the tie bed and to further prevent the disturbing of the ballast already in place; to eliminate insofar as possible the necessity of tamping the tie and the ballast by the section crew.

While in Figs. I and II I have shown a power device of the hydraulic type in which a hand operated pump is employed for pumping the operating fluid, in Figs. III, IV, and V, I have shown the device as being operated by a prime mover as an internal combustion hydrocarbon engine 54. A pump 55 is driven through suitable reduction gears and connections not here shown. The pump fluid passes from the pump 55 through suitable piping connections 56 into a receiving holder 57. The pump 55 receives the fluid from a sump 58 to which sump the pump 57 is connected. A pressure indicator 59 is in communication with the interior of the receiver 57. A safety valve 60 is associated with the pressure indicator 59. The operating fluid is delivered to the cylinder 37 by a suitable piping connection 61. A hand operated valve 62 controls the flow of fluid from the receiver 57 into the pipe 61. A pipe 63 also communicates the receiver 57 with the cylinder 45. A hand manipulated valve 64 is disposed within the pipe 63 to control the flow of fluid from the holder 57 into the cylinder 45.

Each of the tie engaging heads is comprised of a frame 65. The jaws in one side of the head are fixed with one of the jaws 66 being movable. Leader pins 67 are carried by the movable jaws 66. A cylinder 68 is disposed within the frame 65, with a piston 69 being reciprocably disposed within the cylinder and an end of the piston rod 70 being fixed to the movable jaw 66. Operating fluid under pressure is delivered from the receiver 57 through a tube 71 to move the piston rod and the jaw in one direction. A tube 72 delivers a fluid from the receiver 57 into the opposite end 73 of the cylinder 68, thus providing

means for moving the jaw 66 toward and away from the frame 65 of the head. The jaw 66 as well as the opposite end of the head 65 carries a plurality of teeth 74, with the teeth being journaled relative to the jaw and head by suitable pins 75 to provide effective means for grasping the tie by the teeth carried by the jaw and head.

It will be noted that suitable piping 76 and 77 lead from the valve 78 to the respective ends of the cylinder 45 and that the valve 78 is in communication with the receiver 57 through suitable piping connections 79.

I claim:

1. In a device of the class described, in combination with a railway track, a piston and a cylinder with the piston being reciprocably mounted in the cylinder, a pump for supplying a fluid under pressure to the cylinder, an ejecting head carried by the piston rod for engaging a tie on its top surface, a rail-engaging frame to support the cylinder, a tensioning member secured at one end to said frame and having at its other end a bridging board to engage the ends of ties adjacent the tie to be removed, said cylinder being hingedly secured to the rail-engaging frame.

2. In a device of the class described comprising in combination a head, pintle shafts carried by the head, a hydraulic cylinder with the cylinder being hingedly supported upon the pintle shafts, a fluid pump carried by the cylinder and adapted for supplying a fluid under pressure into the cylinder, a sump tank carried by the cylinder, a supporting arm rearwardly extending from the head and disposed above the cylinder and being immovable relative to the head, a spring disposed between the arm and the cylinder to form a counterbalance for the cylinder, a foot disposed upon the lower end of the head and positioned to engage the ball of a railway rail, a tensioning member secured upon its one end to the head and secured upon its opposite end to a boot and to a bridge board, a piston and a piston rod disposed within said cylinder and a tie engaging head hingedly secured to the outer end of the piston rod with said tie engaging head adapted to engage the top of a railway tie to be ejected thereby.

3. In a device of the class described comprising in combination a cylinder, a support for the cylinder with said support adapted to engage each of the rails comprising a railway track for hingedly supporting the cylinder relative thereto, a piston and piston rod associated with the cylinder, a fluid pump for supplying a fluid under pressure into the cylinder and for exerting an outward pressure on the piston and a tie engaging head secured to the outer end of the piston rod and adapted for engaging the top of a railway tie that is to be removed.

4. In a device of the class described in combination with a railway track, comprising a hydraulic cylinder, a head for supporting said cylinder on one of the rails of the track, hinging means for securing the cylinder to the head, a piston, and a piston rod associated with the cylinder, with said cylinder and piston rod being disposed transversely of one of the rails of the track, a tie engaging head carried by the piston rod, and a fluid pump for pumping a fluid into the cylinder for operating the piston disposed in the cylinder and adjustable means for securing the head to the other one of the rails forming the track.

5. In a device of the class described in combi-

nation with a railway track, a hydraulic cylinder, a head carrying pintle shafts for hingedly supporting the cylinder, a tie pushing piston and piston rod powered by a fluid under pressure associated with the cylinder, a tie engaging head carried by the piston rod and means effecting engagement between the tie engaging head and the tie and for imparting longitudinal movement to the tie when engaged by the head and manually manipulative means for motivating the piston within the cylinder.

6. In a device of the class described in combination with a railway track, comprising a cylinder, a support for the cylinder and adapted for supporting the cylinder in superposed position relative to the rails of the track with the cylinder being tiltable relative to the support, a piston rod and a piston associated with the cylinder, a pump adapted for supplying a fluid under

pressure to the cylinder, a tie engaging head carried by the piston rod with said tie engaging head being positioned for engaging the tie between the rails comprising the railway track, and 5 a tension rod carried by the head and arranged to engage adjacent ties to the tie being removed.

7. In a device of the class described in combination with the rails of a railway track, a head adapted for being supported upon the top of one of the rails of a railway track and for being slid therealong, a tie rod, one end of which is secured to the head, the other end of which is secured to the other one of the rails of a railway track, a cylinder hingedly secured to the head, a piston and piston rod associated with the cylinder, a pump in communication with the cylinder, means for actuating the pump and a tie engaging head carried by the piston rod.

HARRY B. HUGHES.
